UNITED STATES PATENT OFFICE.

EDWARD F. FLANAGAN, OF WASHINGTON, DISTRICT OF COLUMBIA.

BINDER FOR MUSIC, &c.

No. 807,734.

Specification of Letters Patent.

Patented Dec. 19, 1905.

Application filed May 4, 1904. Serial No. 206,406.

To all whom it may concern:

Be it known that I, EDWARD F. FLANAGAN, a citizen of the United States, residing at Washington, in the District of Columbia, 5 have invented new and useful Improvements in Binders for Music, &c., of which the following is a specification.

This invention relates to improvements in binders for sheet-music, clippings, &c.; and 10 the object is to provide a simple, cheap, and durable binder having means whereby the music or other matter to be bound may be readily and conveniently inserted and detachably bound together in book form in such a 15 manner that any desired sheet may be removed and replaced or another substituted therefor without disturbing the remaining sheets of music or other matter in the binder.

With the above object in view the invention 20 consists in the novel features of construction hereinafter fully described, particularly pointed out in the claims, and clearly illustrated in the accompanying drawings, in which—

Figure 1 is a view of a binder constructed 25 in accordance with my invention, showing several of the binding-stubs, a sheet to be bound being shown attached to one of the stubs; Fig. 2, an edge view of the same. Figs. 3, 4, and 5 illustrate the method of folding 30 and forming the binding-stubs; Fig. 6, a perspective view, partly in section, of a stub with a folded or double sheet of music or other matter attached thereto; Fig. 7, a view of the inside of one of the boards of the binder-cover, 35 showing a scale or gage to be used in ascertaining the proper points to form the openings in the sheet to be bound to receive the fasteners carried by the stubs; Fig. 8, a perspective view of a modified form of stub with 40 sheets to be bound attached thereto; Fig. 9, an edge view of the same; Fig. 10, a modified way of attaching a sheet or sheets to the stub shown in Fig. 8, and Fig. 11 a modified form of the stub of Fig. 8.

Referring now more particularly to the 45 drawings, Figs. 3, 4, and 5, the numeral 1 designates a strip of paper or light pasteboard, to which a reinforcing-strip 2 of flexible material—linen, cotton, or the like—is secured 50 by pasting or gluing. The reinforced strip thus formed is folded longitudinally at its center, as indicated by dotted line α , Fig. 3, and the folding portions glued or otherwise secured together, pliable U-shaped attaching- 55 staples 3 or other similar fasteners being first inserted, so as to have the legs thereof project

through the portion or fold of the strip. By pasting or gluing the folded portions together the fasteners are held from displacement. As many of these features may be used as may be necessary or desirable. A portion of the two-ply strip thus formed is then folded upon the major portion thereof at the side edge opposite to that carrying the fasteners, as indicated by the dotted line β , Fig. 4, and notches 4 are cut therein at the bend or fold for the binding cords or threads, by means of which the stubs thus formed are bound in a cover 5 in a manner well known in the art of bookbinding. 70

In assembling the stubs as many may be bound together as may be desirable, and between them one or more filler-stubs 6 may be placed, as may be necessary, as illustrated in Fig. 2, said filler-stubs consisting of reinforced 75 strips folded longitudinally at a central point and notched at the bend or fold for the binding cords or threads, or they may consist simply of one or more reinforced strips of material not folded, but of single thickness. 80

In attaching the music or other matter, holes are punched therein, the proper positions of which may be ascertained by placing the inner edge of the sheet along the longitudinal line 7 of a scale placed upon the inner face of one 85 of the boards of the cover or in any convenient place and marking the places for the holes in accordance with the transverse lines 8 of the said gage or scale. The holes are then formed in the sheet and the latter applied to the stub 90 and with the legs of the fasteners projecting through the holes. The projecting legs of the fasteners are then bent down, as indicated in Fig. 6, to secure the sheet to the stub. The fasteners being of pliable material, the legs 95 thereof may be bent and rebent a number of times without breaking, so that the matter attached to the stub may be removed and replaced at will and other matter substituted therefor, the feature being especially convenient and desirable in binding music, as very often, perhaps, only one sheet would be desired for use, and this could be readily removed without disturbing the other sheets, thus avoiding the necessity of carrying the 105 whole binder to the concert-hall or other place where the music is to be used. 100

In Fig. 8 I use a single reinforced strip 9, folded longitudinally to form unequal portions, the wider portion 10 being formed along 111 its single edge with a number of openings 11 to receive ordinary paper-fasteners 12, which

are first passed through openings formed in the sheet *d* to be bound, the proper positions of the openings in the sheet being ascertained by means of the scale before mentioned. As shown in Fig. 10, two of the stubs described with a proper filler-stub 13 therebetween may be utilized in a sheet or group of sheets, the fasteners in this instance passing through both stubs and the sheets.

10 In Fig. 11 I show a stub similar to that shown in Fig. 8, with the exception that fasteners of the type shown in Figs. 1 and 6 are used, this stub being especially convenient, as is also that of Figs. 1, 2, 3, 4, and 5 and 6, 15 for binding double or folded sheets of music or other matter.

In all of the forms shown the sheets may be conveniently and readily attached and detached to and from the binder-stubs.

20 From the above description it will be seen that I have produced a very simple, convenient, and durable binder, in which music or other matter may be readily bound by a person not skilled in bookbinding and removed 25 from the binder without mutilating or otherwise injuring the music, so that a number of sheets may be preserved from loss and damage in a form accessible for reference and use.

Having thus fully described my invention, 30 what I claim as original and desire to secure by Letters Patent of the United States, is—

1. A binder for sheet-music and the like comprising a cover, a plurality of binding-stubs bound in said cover, each stub consisting of a strip folded longitudinally to form portions of unequal width, a plurality of fasteners carried by each stub for detachably connecting the music or other matter thereto, and 35 filler or spacing stubs arranged between the binding-stubs.

2. A binder-stub for sheet-music and the like comprising a reinforced strip folded longitudinally to provide portions of different widths and notched at the fold for the binding-cord, and a plurality of fasteners carried 45 by the wider portion of the strip for detach-

ably connecting the music or other matter to the stub.

3. A binder for sheet-music and the like comprising a stub formed of a strip folded 50 longitudinally with the portions formed by folding united by pasting or gluing, flexible fasteners inserted in said strip before the uniting of the portions thereof formed by folding and projecting through the fold thereof for 55 detachably connecting the music or other matter to the stub, said strip after folding and pasting being folded longitudinally at the edge opposite to the fasteners, and formed with notches at said fold for binding. 6c

4. A binder for magazines, sheet-music, and the like, comprising a plurality of stubs, each consisting of a reinforced strip folded longitudinally with the portions formed by said fold united by gluing or otherwise, flexible 65 fasteners having prongs or legs inserted in said strip before the uniting of the portions formed by folding and projecting through the fold thereof for detachably connecting the music or other matter to the stub, said stubs 70 being formed with a plurality of notches to receive the binding-cord, fillers or spacing-stubs arranged between the binding-stubs, and a cover in which the binding and filler stubs are bound. 75

5. A binder for magazines, sheet-music and the like, comprising a cover, a plurality of binding-stubs bound in said cover, each stub consisting of a reinforced strip formed with notches for the binding-cord, a plurality of 80 fasteners carried by each stub for detachably connecting the music or other matter thereto, and fillers or spacing-stubs arranged between the binding-stubs.

In testimony whereof I have signed my name 85 to this specification in the presence of two subscribing witnesses.

EDWARD F. FLANAGAN.
